BERTH ARRANGEMENT

Basil E. Jones, Flossmoor, Ill., assignor to The Pullman Company, Chicago, Ill., a corporation of Illinois

Application October 15, 1945, Serial No. 622,335

16 Claims. (Cl. 105—317)

1

This invention relates to railway sleeping cars and has particular reference to such cars equipped with berths arranged in vertical tiers with the berths of each tier all disposed in parallel overlying relationship.

The invention contemplates berths disposed in tiers of three, in which at least certain of the berths are foldable and wherein closure members are provided at opposite ends of the berths to close the space therebetween and which are foldable to inoperative positions when the berths are folded.

The principal object of the invention comprises the provision of a foldable berth having berth end closure members hingedly mounted thereon for pivotal movement from folded positions relative to the berth to vertical positions extending between the berth and another berth disposed in parallel relation therewith.

An important object of the invention is to provide a foldable berth having berth end closure members hingedly mounted thereon for pivotal movement from folded positions relative to the berth to vertical positions extending above and below the berth at respectively opposite ends to close the space between the berth and other berths disposed respectively above and below the foldable berth.

Another and more specific object of the invention lies in the provision of a passenger vehicle having a room including a tier of berths disposed parallel to a wall of the room and extending between a vehicle side wall having a window within the area of the berths and an aisle partition having an opening within the area of the berths wherein an intermediate berth in the tier is provided with berth end closure members hingedly mounted thereon at opposite ends and movable from folded positions relative to the berth to vertical positions extending above and below the berth in a manner to cover the window in the side wall and the opening in the aisle partition and thereby close the space at the ends between the intermediate berth and berths disposed above and below the intermediate berth.

The foregoing and other objects are attained by the construction and arrangement illustrated in the accompanying drawings in which

Fig. 1 is a general cross sectional view of a railway passenger vehicle constructed in accordance with the present invention and showing a room disposed between a side wall of the vehicle and an aisle partition with an upper berth extending transversely of the vehicle between the side wall and partition and a foldable intermediate berth disposed in inoperative position immediately beneath the upper berth and a sofa-seat which is convertible to a bed to provide a lower berth, and all operatively disposed in parallel overlying relationship. In this view the

2

berth end closure panels are shown in folded positions in the intermediate berth;

Fig. 2 is a sectional view transversely of the berths taken on the line 2—2 of Fig. 1 showing the various berths in their operative positions, disposed in substantially equally spaced parallel overlying relationship and illustrating the berth end closure members at the aisle position in their vertical operative positions extending above and below the intermediate berth and clearly revealing the relation of these closure members with respect to the open portion of the aisle partition and their function of closing the spaces between the various berths at this end;

Fig. 3 also is a sectional view transversely of the berths in their operative positions but taken on the line 3—3 of Fig. 1 and showing the berth end closure members at the side wall end of the berths disposed in their vertical operative positions extending above and below the intermediate berth on which they are hinged and providing means covering the window, both in the intermediate berth and in the lower berth, and completing the closing of the spaces between the various berths at that end;

Fig. 4 is a sectional view transversely of the vehicle similar to Fig. 1 showing the berths in elevation but to a larger scale and illustrating the berths made up for occupancy with the berth end closure members all operatively disposed in their vertical positions extending above and below the intermediate berth and revealing the manner of releasably securing the upright closure members to the side wall and aisle partition and the depending members to the lower berth;

Fig. 5 is a fragmentary detail sectional view taken on the line 5—5 of Fig. 4 illustrating a section through the berth frame of the intermediate berth and showing the berth end closure member at the lower side of the berth in its closed inoperative position with the releasable securing means at the front side of the berth for maintaining the closure member in this position, engaged in the cooperative bracket projecting from the member;

Fig. 6 is a fragmentary front elevational view of the intermediate berth frame at the position of the securing mechanism illustrated in Fig. 5 and showing the releasable hook on the berth frame engaged within the projecting bracket on the berth end closure member for retaining the member in closed position against the bottom side of the berth;

Fig. 7 is a fragmentary detail sectional view taken on the line 7—7 of Fig. 2 illustrating a partial section through the end wall of the lower berth member and showing the arrangement for releasably securing the end closure member depending from the intermediate berth to the lower berth with the closure member bearing against a

stop plate on the lower berth and a wedge plate on the closure member engaged by a rotatable latch for retaining the closure member in operative vertical position;

Fig. 8 is an elevational view of the securing device illustrated in Fig. 7 from inside the lower berth showing the end closure member disposed between the stop plate on the end wall of the berth and the rotatable latch, with the latch in engagement with the wedge plate on the closure member;

Fig. 9 is a fragmentary detail sectional view taken on the line 9—9 of Fig. 2 illustrating the mechanism for maintaining the berth end closure members at the upper side of the intermediate berth in upright operative position with the closure member shown in vertical position in spaced substantially parallel relation to the aisle wall and a spring pressed catch member pivotally mounted on the closure member releasably engaged with a cooperating bracket on the aisle wall; and

Fig. 10 is a detail plan view of the securing device illustrated in Fig. 9 showing the spring actuated catch member pivotally mounted on the berth end closure member engaged over the hook on the aisle partition with which it is adapted to be associated.

The invention as disclosed herein is applied to a railway passenger vehicle known as a three-tier sleeper, in which berths are arranged in tiers of three disposed in rooms each having one or more tiers of berths so arranged. The accommodations in a vehicle of this type are convertible for day or night use and the conversion from one type of accommodation to the other, from day to night use or vice versa, may readily be performed in a minimum of time. The lower berth is convertible from a bed into a sofa containing a plurality of individual seats for daytime use and the intermediate berth is adapted to be pivoted upwardly into the upper region of the vehicle directly beneath the upper berth so as to provide ample headroom over the sofa. The intermediate berth is supported in a pivotally mounted pan which is adapted to be moved from an upper horizontal position to a depending vertical position when the berth is operatively disposed in the intermediate horizontal position for use as a bed and which serves the twofold function of supporting the berth and forming one wall enclosing the berth. The intermediate berth assembly is counterbalanced by mechanism completely concealed from the berth and from the room. The present invention might be said particularly to relate to the intermediate berth in conjunction with one or the other of the associated berths inasmuch as the structures comprising the primary features of the invention are adapted to be disposed between the intermediate berth and the respective other berths at opposite ends.

In the drawings 10 represents a railway passenger vehicle having side walls 11 and 12, a floor 13 and a roof 14. An aisle partition 15 is disposed in spaced parallel relation to the side wall 11 defining a longitudinal aisle 16 at one side of the vehicle which communicates with a plurality of rooms at the other side of the partition and with a vestibule (not shown) at one end of the vehicle. A plurality of transverse partitions 17 extend between the side wall 12 and the aisle partition and therewith define a number of adjoining rooms 18. Each partition 17 is provided with an opening 19 extending over a substantial portion of its area intermediate the floor 13 and

ceiling 21 so that when the openings are uncovered the effect is had of an open car affording a view throughout the full length of the vehicle. The aisle partition 15 is provided with an entrance opening 22 from the aisle 16, as best illustrated in Fig. 2, and in addition thereto is provided with an opening 23 extending throughout the intermediate area of the partition in the room so that the room might be said to be substantially open to the aisle on that side. As best shown in Fig. 1, the aisle 16 is provided with a ceiling 20 over which a longitudinally extending air duct 24 is mounted and adapted to supply the rooms 18 with conditioned air. Branch ducts 25 and 26 lead from the main duct to the room areas.

Each of the rooms 18 is equipped with sleeping berths which may be disposed in one or more tiers of three berths arranged respectively at one or both sides of the room entrance 22. Each of the tiers of three berths comprises a fixed upper berth 27, a foldable intermediate berth 28 and a convertible lower berth 29 disposed adjacent to and paralleling the respective transverse partitions 17 and extending substantially from the side wall 12 to the aisle partition 15. The upper berth 27 is disposed above the level of the partition opening 19 and comprises a rectangular frame 30 having a flexible base 31 secured thereto at opposite sides and at the two ends and disposed tautly therebetween to provide a flexible support for a mattress 32. The berth frame 30 is supported at opposite ends upon angle members 33 secured respectively to the side wall 12 and to the aisle partition 15 and to which the frame is rigidly secured.

The lower berth 29 comprises a sofa convertible from a seat for daytime use to provide a bed for night use. The sofa includes a seat 34 and a backrest 35 disposed beneath the level of the opening 19 in partition 17 and both the seat and backrest portion are divided into a plurality of spaces for the individual use of the occupants of the respective berths in the tier as best indicated in Fig. 1. The backrest is pivotally mounted at opposite ends as at 36 for movement from a substantially upright position to a horizontal bed forming position and includes a rectangular frame having side rails 37 and end walls 39 and 40, the latter disposed adjacent to the side wall 12 and aisle partition 15 respectively and all including inwardly extending flanges to which a flexible base 41 is secured and maintained taut therebetween for flexibly supporting a mattress 42. The flexible base member 41 and the mattress are concealed by the backrest 35 in the upright seating position of the unit.

The intermediate berth 28 is foldable from the operative position indicated in Figs. 2 and 3 to an inoperative position immediately beneath the upper berth as shown in Fig. 1 and includes a hingedly mounted berth supporting pan 45 extending between the side wall 12 and aisle partition 15 from which it is pivotally supported as at 46 and normally disposed above the level of the partition opening 19 as illustrated in Fig. 1 and indicated in dotted lines in Fig. 2. In this upper horizontal position the pan is supported at its free edge by means of spring pressed releasable catches 47 which automatically engage beneath wear plates on the pan as the latter is moved to final inoperative position. When this pan 45 is moved to its vertical depending position in the operative position of the berth, it completely covers the opening 19 in partition 17 whereby to afford full privacy to the occupants of the various berths.

The sleeping berth proper is mounted in the pan for folding movement relative thereto from a horizontal operative position to a vertical position in the pan and thence with the pan to a horizontal inoperative position adjacent the underside of the upper berth.

The sleeping berth is pivotally mounted in the pan 45 adjacent to that side of the pan opposite the pivotal mounting of the pan itself as at 48 so that the berth may be moved from its folded position in the pan, where it is held at opposite ends by releasable latches 47, to a horizontal operative position intermediate the upper and lower berths. This sleeping berth is similar in construction to the upper berth and comprises a rectangular frame 51 having a flexible base member 52 secured thereto at both sides and at opposite ends and disposed tautly therebetween to provide a resilient supporting surface for mattress 53. The berth frame 51 at its free edge is supported at opposite ends in the horizontal operative position by means of flexible chains 54 attached to the frame 51 and to the fixed upper berth frame 30 and which are receivable in the pan 45 in the folded condition of the intermediate berth. The entire intermediate berth assembly is counterbalanced for ready operation by means of horizontally arranged springs 55 disposed along the aisle partition 15 and side wall 12 and concealed by box-shaped cover plates 56 from the view of the occupants of the room containing the berths. The springs are connected to the berth assembly by means of flexible chains 57 secured respectively at one end to the springs and passing over sprockets 58 to connect at their other ends with the pan 45 at respectively opposite ends and at points 59 removed from the pivot 46 to exert a force counterbalancing the weight of the berth assembly. A window 44 is disposed in the side wall 12 in each room and which it will be noted extends within the area of the berths.

It will be noted that while the openings 23 in the aisle partition 15 contribute to the generally open atmosphere in a vehicle of this type and afford a general view of the aisle to persons using the sofa in the daytime arrangement of the room and permits a greater observation of the room from the aisle, these conditions are not desirable in the disposition of the accommodations for use at night as sleeping berths at which time it is desired to enclose the berths to the fullest extent possible. The berth supporting pan 45 covers the transverse partition opening 19 in each room but the aisle partition opening 23, unless covered, leaves the intermediate and lower berths open at the aisle end. In order to close the spaces between the various berths occasioned by this condition and to cover the window 44 in side wall 12, the invention provides berth end closure members between the upper and intermediate berths and between the intermediate and lower berths at respectively opposite ends. These end closure members, as shown, all are hingedly mounted on the intermediate berth 28 and are adapted to be moved from folded positions relative to the berth to vertical positions extending above and below the berth and secured in these positions by connections with the side wall 12 and aisle partition 15 in the case of the upwardly directed members, and to the lower berth in the case of the downwardly extending members.

The end closure members for use between the intermediate and upper berths comprise a pair of panel members 65 and 66 pivotally mounted at respectively opposite ends of the intermediate 75

berth on the respective end rails 50 by means of continuous piano type hinges 67 and extending substantially full width of the berth. The panel 65, when disposed vertically, is of a height fully to cover that portion of the opening 23 extending above the intermediate berth, as best shown in Fig. 2, and the panel 66 in vertical position amply protects the window 44 from accidental kicking by the occupant of the berth and serves to exclude light from the window as best shown in Fig. 3. Both of the panels 65 and 66, are releasably maintained in their vertical positions by means of similar spring actuated latching devices 70 which are engageable with hooks 68 and 69 mounted on the aisle partition 15 and side wall 12 respectively, and when the room is made up for daytime occupancy the panels may be folded to horizontal positions in the intermediate berth where they are maintained by the pressure of the bedding in the folded position of the berth, as shown in Fig. 1.

The latching devices 70, as best shown in Figs. 9 and 10, are mounted upon the respective closure members 65 and 66 and each comprise a fixed bracket 71 secured to the closure members adjacent the free ends thereof by means of fastenings 72 and a latch piece 73 pivotally mounted in the bracket with a spring 74 operative between the two parts to cause the piece 73 to occupy a folded position lying against the particular panel on which it is mounted when the panels are inoperatively disposed. The latch piece 73 of each securing device is pivoted in the bracket 71 intermediate its ends on an axle member 76 and at one side of the pivot point is formed with a thumb piece 75 by means of which the latch is manipulated, and at the opposite end is provided with an opening 77 adapted to fit over the upstanding hook 68 in the operative disposition thereof. The spring 74 is coiled about the axle 76 in the opening 77 provided therefor in the latch piece, with one end anchored in the bracket 71 and the other end engaging the latch 73 to exert a force in a direction to maintain the latch engaged over the supporting hook 68 whereby releasably to maintain the respective end closure members in operative positions. The length of the latch piece is such as to maintain the closure members substantially vertical in parallel relation to the side wall 12 and aisle partition 15 respectively, and when disengaged from the hook 68 is adapted to lie flat against the panel 65 or 66, as the case may be, under pressure exerted by the spring 74.

The end closure members for use between the intermediate and lower berths comprise a pair of panel members 81 and 82 pivotally mounted adjacent respectively opposite ends of the intermediate berth 28 at the underside by means of continuous piano type hinges 83. The panel 81 at that end of the berths adjacent the aisle partition 15, as best shown in Fig. 2, is of a width and of such height as fully to cover that portion of the opening 23 in the aisle partition extending below the intermediate berth when the panel is disposed in its vertical position and the panel 82 at the opposite end of the berths, as best shown in Fig. 3, completely covers the portion of window 44 extending within the area of the berths. Both of the panels, 81 and 82, are releasably maintained in their vertical positions by similar means, fixing such positions of the panels relative to the respective end walls 39 and 40 of the lower berth. As best shown in Figs. 7 and 8, which illustrate the condition of panel 81 relative to the lower berth end wall 40 but which is also

representative of the condition of the panel 82 with respect to the berth end wall 39, the lower berth is provided with upstanding stop plates in the form of angle members 84 mounted upon the upper surface of the respective end walls 39 and 40 and secured by screws 86 and disposed in position to be engaged by the respective panel members as they are swung to operative positions and thereby limit their final position of movement in regard to the berth end walls to that shown in Fig. 7. As shown in this figure, a rubber bumper 81 is disposed between the berth and closure panel and the stop plate 84.

When the end closure panels are moved to their depending vertical positions indicated, they may each be secured at the respective inner sides by means of a swinging latch member 85 which is pivotally mounted on the inner side of the lower berth end wall for movement from a depending inoperative position to an upright locking position, where it is disposed in engagement with a wedge plate 88 secured on the face of the respective panel members adjacent the lower edge. The wedge plate is shaped for approach by the latch 85 from either side and has its greatest depth at the center locking position of the latch where it is provided with a vertically disposed V-shaped groove 89 which is engaged by a similarly shaped projection 90 on the latch member to maintain the latch in locking position. The latch is readily releasable since the resiliency of the bumper 81 will permit sufficient deflection of the closure panel to enable the projection 90 to pass the wedge plate, and a thumb piece 91 on the latch provides for its ready manipulation.

The berth end closure panels 81 and 82 are movable from their depending operative positions described, to inoperative positions against the underside of the intermediate berth, as indicated in dotted lines in Figures 1 and 4, where they are supported during the folding movements of the berth by releasable securing devices best illustrated in Figures 5 and 6. The panels 81 and 82 are each provided with a laterally projecting fixed hasp member 95 at the front edge of the respective panels and adjacent that end thereof farthest removed from the hinge 83 adapted to be engaged by releasable supporting hooks 96 pivotally mounted on the outer face of the intermediate berth frame 51 in position to be engaged with hasps 95 as the panels are swung to horizontal position against the underside of the intermediate berth to maintain the closure panels in their folded inoperative positions bearing against resilient bumpers 97. The hasp members 95, while projecting laterally from the panels 81 and 82, are bent at right angles as at 98 to provide a portion extending upwardly in the inoperative position of the panels and having an opening 99 through which the hook 96 is adapted to engage in the support of the respective panel members.

From the foregoing it will be seen that closure means are provided for fully enclosing the ends of the lower and intermediate berths and which are foldable into one of the berths when the room is made up for daytime occupancy, but which are readily accessible when the berths are opened for use and easily set up and secured in operative positions. The berths are all adapted to be enclosed by curtains, which have not been shown since they form no part of the present invention but which afford complete privacy and individual access to each of the three berths in the tier. The berths are each provided with a fabric shelf for the accommodation of articles placed thereon by

the occupants. In the upper berth the shelf 60, as shown in Fig. 1, is mounted at the side wall 12, but in the intermediate berth and in the lower berth the shelves 61 and 62 are mounted upon the berth end closure panel members 66 and 82 respectively, as shown in Figs. 3 and 4. The shelves, being of fabric, are collapsible when not in use, and when the end closure members are folded to inoperative positions in the intermediate berth, the shelves 61 and 62 are automatically flattened for accommodation in the berth.

What is claimed is:

1. In a passenger vehicle having a lower berth, an intermediate berth and an upper berth all disposed in parallel overlying relationship, said lower berth being convertible into a seat having a seat portion and a backrest and said intermediate berth being foldable to an inoperative position providing headroom above said seat, means for closing the space between the various berths at respectively opposite ends comprising end closure members foldable into the intermediate berth in the inoperative position thereof and movable to vertical positions extending respectively between the intermediate berth and the upper berth and between the intermediate berth and the lower berth when all of the berths are disposed in operative positions, means releasably securing the end closure members in vertical position, and means maintaining said members in folded position in the inoperative position of the intermediate berth.

2. In a passenger vehicle having a lower berth, an intermediate berth and an upper berth all disposed in parallel overlying relationship, said lower berth being convertible into a seat having a seat portion and a backrest and said intermediate berth being foldable to an inoperative position providing headroom above said seat, means for closing the space between the various berths at respectively opposite ends comprising a pair of end closure members hingedly mounted on the intermediate berth and movable from inoperative folded positions to positions vertically disposed between the intermediate and upper berths, a pair of end closure members hingedly mounted on the intermediate berth and movable from inoperative folded positions to positions vertically disposed between the intermediate and lower berths, means releasably securing the end closure members in vertical position, and means maintaining said members in folded position in the inoperative position of the intermediate berth.

3. In a passenger vehicle having a lower berth, an intermediate berth and an upper berth all disposed in parallel overlying relationship, said lower berth being convertible into a seat having a seat portion and a backrest and said intermediate berth being foldable to an inoperative position providing headroom above said seat, means for closing the space between the various berths at respectively opposite ends comprising a pair of end closure members hingedly mounted on the intermediate berth and movable from inoperative folded positions to positions vertically disposed between the intermediate and upper berths, and a pair of end closure members hingedly mounted on the intermediate berth and movable from inoperative folded positions to positions vertically disposed between the intermediate and lower berths.

4. In a passenger vehicle having a lower berth, an intermediate berth and an upper berth all disposed in parallel overlying relationship, said intermediate berth being foldable to an inoperative position, means for closing the space between the

various berths at respectively opposite ends comprising a pair of end closure members hingedly mounted on the intermediate berth and movable from inoperative folded positions to positions vertically disposed between the intermediate and upper berths, and a pair of end closure members hingedly mounted on the intermediate berth and movable from inoperative folded positions to positions vertically disposed between the intermediate and lower berths.

5. In a passenger vehicle having a lower berth, an intermediate berth and an upper berth all disposed in parallel overlying relationship, said lower berth being convertible into a seat having a seat portion and a backrest, said intermediate berth being foldable to an inoperative position adjacent the underside of the upper berth to provide headroom for said seat and comprising an assembly including an intermediate berth member and a pan having its open side facing upwardly when the intermediate berth is disposed adjacent the upper berth, said pan being pivotally mounted for movement from a horizontal position adjacent the upper berth to a vertical position and said intermediate berth member being pivotally mounted in the pan for movement from a folded position in the pan to a horizontal operative position, means for closing the space between the various berths at respectively opposite ends comprising a pair of end closure members hingedly mounted on said intermediate berth member and movable from inoperative folded positions in the intermediate berth to upright operative positions disposed between said berth member and the upper berth, and a pair of end closure members hingedly mounted on the intermediate berth member and movable from inoperative folded positions in the intermediate berth to operative positions vertically disposed between said berth member and the lower berth.

6. In a passenger vehicle having a lower berth, an intermediate berth and an upper berth all disposed in parallel overlying relationship, said intermediate berth being foldable to an inoperative position adjacent the underside of the upper berth and comprising an assembly including an intermediate berth member and a pan having its open side facing upwardly when the intermediate berth is disposed adjacent the upper berth, said pan being pivotally mounted for movement from a horizontal position adjacent the upper berth to a vertical position and said intermediate berth member being pivotally mounted in the pan for movement from a folded position in the pan to a horizontal operative position, means for closing the space between the various berths at respectively opposite ends comprising a pair of end closure members hingedly mounted on said intermediate berth member and movable from inoperative folded positions in the intermediate berth to upright operative positions disposed between said berth member and the upper berth, a pair of end closure members hingedly mounted on the intermediate berth member and movable from inoperative folded positions in the intermediate berth to operative positions vertically disposed between said berth member and the lower berth, means releasably securing said end closure members in operative positions, and means releasably securing certain of said end closure members in folded positions relative to said intermediate berth member.

7. In a passenger vehicle having a lower berth, an intermediate berth and an upper berth all disposed in parallel overlying relationship, said in-

termediate berth being foldable to an inoperative position, means for closing the space between the various berths at respectively opposite ends comprising end closure members foldable into

5 the intermediate berth in the inoperative position thereof and movable to vertical positions extending respectively between the intermediate berth and the upper berth and between the intermediate berth and the lower berth when all 10 of the berths are disposed in operative positions.

8. In a passenger vehicle having an aisle extending longitudinally of the vehicle adjacent to one of the vehicle sides and a room adjacent to the other side with transverse partitions extending

15 from the side wall on the room side to the aisle, said partitions with said side wall defining the room, the room being open at the aisle side, a berth disposed in the upper region of the room,

20 a second berth disposed in parallel relation beneath the first berth in operative position and foldable to an inoperative position, a lower berth beneath the second berth, and means for closing the space between the various berths at their ends adjacent said aisle comprising a pair of end 25 closure members hingedly mounted on the second berth and movable respectively from inoperative folded positions on the berth to operative positions extending vertically between said second berth and said first-named berth and said

30 lower berth disposed respectively above and below the second berth.

9. In a passenger vehicle having an aisle extending longitudinally of the vehicle adjacent to one of the vehicle sides and a room adjacent to 35 the other side with transverse partitions extending from the side wall on the room side to the aisle, said partitions with said side wall defining the room, the room being open at the aisle side, a berth disposed in the upper region of the room,

40 a second berth disposed in parallel relation beneath the first berth in operative position and foldable to an inoperative position, a lower berth in parallel relation beneath the second berth, means for closing the space between the various

45 berths at respectively opposite ends comprising a pair of end closure members hingedly mounted on the second berth and movable from inoperative folded positions in the berth to upright operative positions disposed between the second

50 berth and the first-named berth, and a pair of end closure members hingedly mounted on said second berth and movable from inoperative folded positions in the berth to operative positions vertically disposed between said second 55 berth and the lower berth.

10. In a passenger vehicle having a plurality of berths disposed in parallel overlying relationship, one of said berths being foldable to an inoperative position, and a pair of end closure 60 members hingedly mounted on said foldable berth and movable from folded positions in said berth to positions at one end thereof extending vertically between said berth and other berths disposed respectively above and below said foldable berth.

11. In a passenger vehicle having a plurality of berths disposed in parallel overlying relationship, one of said berths being foldable to an inoperative position, and pairs of end closure members hingedly mounted on said foldable berth at 70 respectively opposite ends thereof and movable from folded positions in the berth to positions extending vertically between said berth and other berths disposed respectively above and below said 75 foldable berth.

12. In a passenger vehicle having a plurality of berths disposed in parallel overlying relationship, one of said berths being foldable to an inoperative position, and end closure member hingedly mounted on said foldable berth and movable from a folded position in the berth to an upright position extending above the berth at one end, means for maintaining said closure member in upright position, an end closure member hingedly mounted on said foldable berth and movable from a folded position relative to the berth to a vertical position depending from said berth at one end, and means for maintaining said last-named closure member in vertical position, said end closure members serving at least partially to close the space between said foldable berth and berths disposed respectively above and below the foldable berth.

13. In a passenger vehicle having a plurality of berths disposed in parallel overlying relationship, one of said berths being foldable to an inoperative position, a pair of end closure members hingedly mounted on said foldable berth and movable from folded positions in the berth to upright positions extending above the berth at respectively opposite ends thereof, means for releasably maintaining said closure members in upright position, a second pair of end closure members hingedly mounted on the foldable berth and movable from folded positions relative to the berth to vertical positions depending from said berth at respectively opposite ends thereof, and means for releasably maintaining said second pair of closure members in vertical position, all of said end closure members serving at least partially to close the space between said foldable berth and berths disposed respectively above and below the foldable berth.

14. In a passenger vehicle having an aisle extending longitudinally of the vehicle adjacent to one of the vehicle side walls, a partition paralleling said wall defining the width of said aisle, a room adjacent to the other side with transverse partitions extending from the side wall on the room side to said aisle partition, said last-named side wall, the transverse partitions and the aisle partition defining said room, said aisle partition being open over a substantial portion of its area within the limits of said room, a plurality of berths in the room disposed in parallel overlying relationship adjacent to one of said transverse partitions, one of said berths being foldable to an inoperative position, an end closure member hingedly mounted on said foldable berth and movable from a folded position in the berth to an upright position extending above the berth at the end thereof adjacent to the aisle partition, means for releasably securing the closure member to said aisle partition to maintain said upright position, a second closure member hingedly mounted on the foldable berth and movable from a folded position relative to the berth to a vertical position depending from said berth at the end thereof adjacent the aisle partition, and means for releasably securing the second closure member to maintain said vertical position, said closure members serving at least partially to close the space between said foldable berth and berths disposed respectively above and below the foldable berth and with said aisle partition fully closing said space, the open area of said aisle partition in the region of said berths being fully closed by the closure members.

15. In a passenger vehicle having an aisle extending longitudinally of the vehicle adjacent to one of the vehicle side walls, a partition paralleling said wall defining the width of said aisle, a room adjacent to the other side with transverse partitions extending from the side wall on the room side to said aisle partition, said last-named side wall, the transverse partitions and the aisle partition defining said room, said aisle partition being open over a substantial portion of its area within the limits of said room between said transverse partitions, said last-named side wall having a window therein disposed in the area between the transverse partitions, a plurality of berths in the room disposed in parallel overlying relationship adjacent to one of said transverse partitions and extending substantially continuously between said last-named side wall and the aisle partition, one of said berths being foldable to an inoperative position, a pair of end closure members hingedly mounted on said foldable berth and movable from folded positions in the berth to upright positions extending above the berth at respectively opposite ends adjacent to said last-named side wall and the aisle partition respectively, means for releasably securing the closure members in their upright positions to said side wall and aisle partition respectively, a second pair of closure members hingedly mounted on the foldable berth and movable from folded positions relative to the berth to vertical positions depending from the berth at respectively opposite ends thereof adjacent to the last-named side wall and aisle partition respectively, and means for releasably securing said second pair of closure members in vertical position, said closure members serving at least partially to close the space between the foldable berth and berths disposed respectively above and below the foldable berth, the open area of said aisle partition in the region of the berths being fully closed by the closure members at that end of the berths and said window being fully covered in the region of the berths by the closure members at that end of the berths.

16. A berth assembly comprising a berth pan pivotally mounted at one side for movement from an out-of-the-way horizontal position to a vertical position, a berth pivotally mounted in the pan at the side opposite said one side and movable from a folded position in the pan when the pan is horizontal to a position substantially at ninety degrees to the pan in the vertical position thereof, and pairs of end members pivotally mounted on said berth at respectively opposite ends for movement from folded positions relative to the berth to vertical positions extending respectively above and below the berth, said members in their folded positions being receivable into said pan with the berth.
